FENDER WELT

Glen G. Barr, Union City, Ind., and Albert H. Kirchner, Washington, D. C., assignors to Backstay Welt Company, Union City, Ind., a corporation of Indiana

Application August 26, 1936, Serial No. 98,036

7 Claims. (Cl. 280—152)

Our invention relates to fender welts, i. e., cushioning strips adapted to be interposed between certain sheet metal parts of automobiles, such as between the body and fenders, to prevent squeaks, rattles, etc. An important object of the invention is to provide a fender welt having an ornamental weatherproof exterior portion and an efficient cushioning and sound-deadening interior portion.

10 Further objects are concerned with generally improving the durability of the sound-deadening portion under adverse conditions consequent upon loosening of the juxtaposed metal parts and relative movement of the same, resulting in rubbing of the welt.

15 A further important object is the provision of a fender welt structure the sound-deadening portion of which can be readily made in any desired thickness to suit the exigencies of particular installations and preferences.

20 Another object is to provide a fender welt of materials which are inexpensive, efficient and durable, which can be satisfactorily die cut, and which will possess a high degree of flexibility.

25 An important principle of the invention resides in the use, in the cushioning or sound-deadening portion of the welt, of a crimped or crepe paper, employed preferably in a plurality of plies bonded together by a suitable waterproof adhesive and 30 filler. We have found that crepe paper, the particular character of which will be more fully explained hereinafter, possesses certain important properties which render it definitely superior to any cushioning material which, so far as we are

35 aware, has ever been heretofore used in fender welt constructions. In its broad aspects the invention contemplates the use of this type of paper, and in certain embodiments of the invention the paper is specially folded and is associated 40 with other elements of the welt in a particular fashion to produce a structure having certain additional advantages, as will be explained hereinafter.

45 The invention is shown in certain preferred forms of embodiment in the accompanying drawing, in which each of the figures is a perspective view, showing one end in cross section, and in all of which the same reference numerals designate corresponding parts.

50 In the drawing, Figs. 1 to 4, inclusive illustrate various forms of the fender welts proposed by our invention, and Fig. 5 shows, on an enlarged scale, a fragment of the crepe paper material which constitutes an important element of the construction.

5 Referring now to the drawing, the reference numeral 1 designates generally the external portion of a fender welt, i. e., the beaded edge which is exposed to view and to the weather when the interior portion, designated by the reference numeral 2, is interposed in operative position between adjacent and generally parallel surfaces of two metal bodies, as for example an automobile body and the attaching flange of a fender. The portion 1 is conveniently made beaded, as 10 by disposing a ply of ornamental weather-resistant fabric 3 around a filler cord 4. The material 3 is conveniently a coated textile fabric of the class generically called imitation leather, and the filler 4 may be a cord of twisted paper, cotton, 15 jute, or the like. The covering for the filler is extended in two spaced parallel plies from a side of the filler. One of these plies, designated 5 in Figs. 1, 2, and 3, is extended a considerable distance from the bead filler to receive and support 20 the sound-deadening material which comprises an important element of the interior portion 2 of the welt, and the other ply of the bead-covering fabric, designated 6 in all the figures, extends a much shorter distance from the filler. The 25 sound-deadening material is interposed between the plies 5 and 6, which may be stitched together, preferably close to the bead filler, as shown at 7 in Figs. 1, 3, and 4, or these two plies may be secured to the sound-deadening material by the 30 use of cement only, as shown in Fig. 2.

The sound-deadening material which forms the important and operative part of the portion 2 of the welt is, according to the principles of our invention, built up of crepe paper employed in a 35 plurality of superposed plies 8, 8. Crepe paper is paper having a multiplicity of surface irregularities, comprising alternate juxtaposed ridges and depressions of more or less minute but readily discernible character. As a rule, the paper is originally smooth-surfaced and of uniform thickness and is subsequently creped by causing it to pass between rollers which introduce the characteristic surface folds. This type of crepe paper is shorter in at least one dimension than the original sheet from which it was formed, and it is 45 freely extensible in the direction of that dimension when placed under tension to straighten out the crimps or folds. This type of crepe paper, shown in Fig. 5, is the form preferred for the 50 sound-deadening element of our invention, but we may use a paper of a somewhat different type, i. e., one which has been originally calendered to provide the desired surface elevations and depressions. It is to be understood that the term 55

"crepe paper" as used throughout this specification and in the appended claims includes originally smooth paper which has been crimped, as well as paper initially formed with surface elevations and depressions.

The crepe paper is used in a plurality of plies 8, 8, securely bonded together by an adhesive such as a latex or asphaltum compound, which is weather-resistant and more or less permanently flexible. The portion 2 of the welt is capable of being provided in any desired thickness, within a relatively wide range of limits, to suit different installations and manufacturers' preferences, by the simple expedient of using 15 plies of paper in greater or less number. This feature constitutes a distinct advantage of our invention and overcomes the difficulty heretofore experienced with welts in which the portion to be interposed between the metal surfaces of 20 the automobile was made of textile fabric. Textile material suitable for use of this kind is inherently thicker than the paper which we employ, and it is not practical to use it in more than a single ply, exclusive of the attaching 25 ply of coated fabric. Attempts to provide cushioning portions of multi-ply textile fabric have been uniformly unsuccessful because the resulting body was in the great majority of cases either too thick or too thin. No known textile fabric 30 having cushioning properties and the requisite strength is available in sheets of sufficient thinness to permit accurate gauging of plural ply thickness.

We are aware of the disclosure in United States 35 Patent No. 1,808,259, issued to Robert C. Schemmel on June 2, 1931, of the substitution of a ply of a relatively heavy grade of paper for the customary textile fabric of the internal portion 2 of the fender welt. Our present invention 40 is to be distinguished from the paper ply of the Schemmel patent in several important respects. The Schemmel paper was a relatively heavy grade, was smooth-surfaced, and was employed in a single ply only. Its thickness prevented its use in plural plies, and in every respect 45 except cost it was indistinguishable from the common textile fabric which it supplanted.

The portion 2 of our fender welt, formed as hereinabove described, is a cushioning body of 50 relatively great compressibility, characterized by a surface having a multiplicity of alternate depressions and elevations. The cushioning body is exceedingly durable, and is very securely united to the bead portion 1 by the ply 5 which backs 55 and supports it.

A good fender welt must be flexible and capable of being readily curved in the plane of its web portion without appreciable distortion thereof. This is necessary to accommodate the 60 welt to the curved contours of automobile fenders and the like. An important advantage of our composite crepe paper body is its possession of these two qualities in high degree, practically 65 without regard to the thickness to which the body may be built up.

In the form of the invention shown in Figs. 1 and 2 the sound-deadening material is disposed on one face only of the skirt or web portion of 70 the welt. Fig. 3 illustrates a modification in which the multi-ply body is originally provided in twice the width desired for the skirt. Half of the body is folded back on itself, with the portion 5 of the covering fabric for the bead 75 filler interposed between the two halves. There

is thus provided a resilient, yielding, sound-deadening surface of both sides of the web.

In Fig. 4 a further modification is shown. In this form of the invention the portion 9 of the bead filler covering fabric 3 is made somewhat 5 narrower than the portion 5 shown in Figs. 1-3, and the plural plies of sound-deadening material are made somewhat wider than as shown in Figs. 1 and 2 and somewhat narrower than as 10 shown in Fig. 3, so that a portion of the plural ply body may be folded over on itself and its edge butted against the extreme edge of the portion 9. The plies of sound-deadening material may be made as thick as, or somewhat thicker than, the ply 9, so that when the welt is 15 compressed between the two metallic surfaces both surfaces of the metal will be separated by the sound-deadening material. The Fig. 4 form of construction has the advantage, possessed also by the Fig. 3 construction, of providing a cushioning surface for both metal surfaces, and in addition it has the advantage, lacking from the Fig. 3 construction, of presenting no exposed raw 20 edge of multi-ply material adjacent to the bead 25 1, which of course in practice is exterior of the metal parts and exposed to the weather.

Figs. 1 to 4 inclusive may be regarded as showing complete fender welts ready for perforation to accommodate the usual bolts which secure the 30 metal parts together, or they may be thought of as blanks which can be die cut or otherwise operated upon to transform the web portions 2 into tongued or pronged strips, as contemplated by the Drangeid Patent No. 1,760,838 and the 35 Schemmel Patent No. 1,808,259.

The welt is applied in the usual manner between the fender flange and the body and the customary bolts are drawn tight, compressing the cushioning portion 2 of the welt. In time, relative movement of the body and fender rubs the 40 paper surface and wears it smooth, flattening down its elevations. The yieldability and resiliency of the superposed piles of paper and adhesive are such that the somewhat diminished 45 thickness of the worn body remains great enough to cushion the metal parts, and there is no fraying or tearing of the cushioning body or the fibers thereof such as occurs when woven material wears under similar conditions of use.

It is believed that the principles of the invention will be understood from the foregoing description of certain preferred forms of embodiment. It is to be understood that the invention is capable of embodiment in still further modified forms, and all such modifications, to the extent 55 that they incorporate the principles of the invention as defined by the appended claims, are to be deemed within the scope and purview thereof.

We claim:

1. A fender welt adapted to be interposed between adjacent flat metallic surfaces in an automobile body or the like to prevent squeaks, rattles and the like, said welt comprising an edge bead 65 and a web extending laterally therefrom, said web being built up of plural plies of creped paper impregnated with and bonded together by a water-resistant substance.

2. A fender welt adapted to be interposed between adjacent flat metallic surfaces in an automobile body or the like to prevent squeaks, rattles and the like, said welt comprising an edge bead and a web extending laterally therefrom, said web being built up of plural plies of creped 70 75

paper impregnated with and bonded together by an asphaltic compound.

3. A fender welt adapted to be interposed between adjacent flat metallic surfaces in an automobile body or the like to prevent squeaks, rattles and the like, said welt comprising an edge bead and a web extending laterally therefrom, said web being built up of plural plies of creped paper impregnated with and bonded together by a latex solution.

4. A fender welt comprising a layer of fabric having a tensile strength greater than that of creped paper, a bead filler encased in a marginal portion of said fabric to provide an edge bead from a side of which the body of the fabric extends, and a ply of paper folded around the body of the fabric and its opposite marginal edge and secured to and supported by said body to form the web portion of the welt.

20 5. A fender welt comprising a layer of fabric having a tensile strength greater than that of creped paper, a bead filler encased in a marginal portion of said fabric to provide an edge bead from a side of which the body of the fabric extends, and superposed plural plies of creped paper bonded together by a water-resistant substance folded around the body of the fabric and its

opposite marginal edge and secured to and supported by said body to form the web portion of the welt.

6. A fender welt comprising a layer of textile fabric having a hard surface coating which is 5 resistant to water, a bead filler encased in a marginal portion of said fabric to provide an edge bead from a side of which the body of the fabric extends, and superposed plural plies of creped paper bonded together by a water-resistant substance 10 folded around the body of the fabric and its opposite marginal edge and secured to and supported by said body to form the web portion of the welt.

7. A fender welt comprising a layer of fabric 15 having a tensile strength greater than that of creped paper, a bead filler encased in a marginal portion of said fabric to provide an edge bead from a side of which the body of the fabric extends, and plies of paper impregnated with a 20 water-resistant substance secured to and supported by the opposite surfaces of the body of the fabric and having one free edge butted against the free edge of the body of fabric.
